UNITED STATES PATENT OFFICE.

PETER BROTHERHOOD, OF LAMBETH, COUNTY OF SURREY, ENGLAND.

VALVE-GEAR.

SPECIFICATION forming part of Letters Patent No. 323,270, dated July 28, 1885.

Application filed March 24, 1885. (No model.) Patented in England March 6, 1885, No. 2,965.

To all whom it may concern:

Be it known that I, PETER BROTHERHOOD, a citizen of England, residing at Lambeth, in the county of Surrey, England, have invented 5 a new and useful Admission Valve and Gear for Multiple-Cylinder Engines, (for which I have applied for a patent in Great Britain, dated March 6, 1885, No. 2,965,) of which the following is a specification.

10 My invention relates to the construction and arrangement of the admission-valve and gear for working it to be used in multiple-cylinder engines, particularly those of the kind known as "Brotherhood engines," whether 15 they are worked by steam or by compressed air, for torpedoes.

I will describe my invention, referring to the accompanying drawings.

Figure 1 is a vertical section of a three-cylinder Brotherhood engine. Fig. 2 is a vertical section on a plane at right angles to that of Fig. 1. Fig. 3 is a part section on the line α α of Fig. 2; and Fig. 4 is a plan showing part of the cam-path developed.

25 On a short spindle, A, let into the end of the engine-shaft with a sliding feather, I fix a barrel-cam, B, in the path of which is engaged a rounded roller, C, mounted on one end of a lever, D, which is pivoted at E. In 30 the other end of the lever D there is a hollow which engages a semi-cylindrical slide, F, pressed forward by a spring, G, said slide having its seat against the lower surface of the cylinder-cover M. This slide is, by means of 35 the cam B and lever D, caused to move to and fro on the lower facing of the cylinder-cover H, through which there is a passage leading into the cylinder.

When the slide is in the dotted position F', 40 the working fluid, which is supplied to the cavity K, passes into the cylinder propelling the piston until the cut-off is effected by the return of the slide, whereupon the piston is

caused to continue its stroke by expansion of the fluid behind it. When the piston uncovers the lateral ports L, a portion of the fluid escapes into the central cavity of the engine, and as the piston makes its return-stroke, after covering the ports L, the residue of the fluid escapes through the port M in the joint of the 45 connecting-rod.

It is to be understood that I do not claim as part of my present invention the use of ports, such as L and M, for exhaust.

Having thus described the nature of my 55 invention and the best means I know of carrying the same into practical effect, I claim—

1. The combination, with a cylinder of a multiple-cylinder engine, of the slide F, located entirely beneath and having its seat upon the lower surface of the cylinder-cover M, the lever D, pivoted between its ends, and the cam B, substantially as described.

2. The combination, with the cylinder of a multiple-cylinder engine, of a semi-cylindrical 60 slide, F, seated upon the lower surface of a cylinder-cover, a lever, D, pivoted between its ends and having a cup-shaped outer end into which is seated the slide, and the cam B, substantially as described.

3. The combination, with the cylinder of an engine, of the slide F, seated upon the lower side of a cylinder-cover, the lever pivoted between its ends, a spring, G, carried by the lever and pressing the slide upon its seat, and 75 the cam B, substantially as described.

In testimony whereof I have signed my name to this specification, in the presence of two subscribing witnesses, this 7th day of March, A. D. 1885.

PETER BROTHERHOOD.

Witnesses:

HERBERT E. DALE,
WALTER JAMES S. RERTER,
Both of 17 Gracechurch St., London.
